Des. 1181

Henry G. Thompson, of New York, N.Y.,
Assignor of Hartford Carpet Company of Hartford.
Letters Patent No. 1181, dated Dec. 20, 1856.

The schedule referred to in these Letters Patent and making part of the same.

To all whom it may concern:

Be it Known that I, Henry G. Thompson, of the City, County and State of New York, have invented or produced a new and original design to be wrought into Venetian Carpeting, or other fabrics, in colors similar to those painted on the drawings accompanying this specification, or in other colors substituted in the place of those painted on the drawings accompanying this specification, and I do hereby declare that the drawings accompanying this Specification do give and convey to any one acquainted with the art of Venetian Carpet Weaving a more defined and thorough description of the nature of my invention than it is in the power of language otherwise to convey and is sufficient to enable any one skilled in the art of Venetian Carpet Weaving to use my invention.

What I claim as my invention and desire to secure by Letters Patent, is the Configuration of the Design hereunto annexed, irrespective of colors and width when made by being wrought into a Twilled Venetian or other Carpet, in form similar to the drawings accompanying this Specification.

Witnesses.
